CLAIM

We claim the ornamental design for detergent capsule, as shown and described.

DESCRIPTION

The patent or applicaiton file contains at least one drawing executed in color. Copies of this patent or patent application publication with color drawings will be provided by the Office upon request and payment of the necessary fee.

FIG. 1 is a right front perspective view of a detergent capsule according to the new design;

FIG. 2 is a rear elevation view thereof;

FIG. 3 is a front elevaiton view thereof;

FIG. 4 is a left elevation view thereof;

FIG. 5 is a right elevation view thereof;

FIG. 6 is a top plan view thereof; and

FIG. 7 is a bottom plan view thereof.

FIG. 8 is a right front perspective view of a detergent capsule according to the new design;

FIG. 9 is a rear elevation view thereof;

FIG. 10 is a front elevation view thereof;

FIG. 11 is a left elevation view thereof;

FIG. 12 is a right elevation view thereof;

FIG. 13 is a top plan view thereof; and

FIG. 14 is a bottom plan view thereof.

FIG. 15 is a right front perspective view of a detergent capsule according to the new design;

FIG. 16 is a rear elevation view thereof;

FIG. 17 is a front elevation view thereof;

FIG. 18 is a left elevation view thereof;

FIG. 19 is a right elevation view thereof;

FIG. 20 is a top plan view thereof; and

FIG. 21 is a bottom plan view thereof.

FIG. 22 is a right front perspective view of a detergent capsule according to the new design;

FIG. 23 is a rear elevation view thereof;

FIG. 24 is a front elevation view thereof;

FIG. 25 is a left elevation view thereof;

FIG. 26 is a right elevation view thereof;

FIG. 27 is a top plan view thereof; and,

FIG. 28 is a bottom plan view thereof.
